JOSEPH RAUWALD, SR., AND FRANK RAUWALD, OF MILWAUKEE, WISCONSIN.

WINDOW-SASH.

1,274,782.

Specification of Letters Patent.

Patented Aug. 6, 1918.

Application filed February 23, 1917. Serial No. 150,543.

To all whom it may concern:

Be it known that we, JOSEPH RAUWALD, Sr., and FRANK RAUWALD, citizens of the United States, and residents of Milwaukee, 5 in the county of Milwaukee and State of Wisconsin, have invented new and useful Improvements in Window-Sashes, of which the following is a description, reference being had to the accompanying drawings, 10 which are a part of this specification.

This invention relates to improvements in window sash and more particularly to the means for securing the panes of glass in the sash.

15 Window sashes as now ordinarily manufactured are rabbeted or grooved on one side to receive the glass which is held in position by painters' three cornered tacks and putty, the tacks serving to hold the 20 glass in position while the putty sets or becomes sufficiently hard to firmly hold the glass in place. The putty is applied with a putty knife and pressed into the corner space and forms a strip of putty of triangular 25 shape in cross section, the lower face of which adheres to the sash bar and side face adheres to the glass. As the surfaces of both the glass and the sash bar are perfectly smooth the adherent quality of the putty is 30 depended upon to hold the putty on the glass and bar. Ofttimes the putty in hardening does not properly adhere to the parts and breaks away in places. This breaking away presents an unsightly appearance and 35 the glass loosens and in the course of time will fall out unless putty is again applied to the parts.

It is one of the objects of the present invention to overcome the before mentioned 40 objectionable features and provide a window sash with means for causing the putty to firmly adhere and be bound to the sash in such a manner as to anchor the putty to the sash.

45 A further object of the invention is to provide a window sash having lines of indentations adjacent to and under the glass into which the putty embeds when in a soft state.

50 A further object of the invention is to provide a window sash which is of simple construction, is strong and durable and does not add materially to the cost of manufacture of the sash.

55 With the above and other objects in view

the invention consists of the improved window sash and its parts and combinations as set forth in the claims, and all equivalents thereof.

In the accompanying drawing in which 60 the same reference characters indicate the same parts in all of the views:

Figure 1 is a fragmentary side view of a window sash made in accordance with the 65 improved construction;

Fig. 2 is a transverse sectional view thereof taken on line 2-2 of Fig. 1;

Fig. 3 is an inner edge view of a portion of the sash;

Fig. 4 is a transverse sectional view of a 70 modified form of sash; and

Fig. 5 is an inner edge view thereof.

Referring to the drawing the numeral 8 indicates a window sash of rectangular 75 shape which is formed of vertical and transverse sash bars 9 and 10 connected together at their end portions. The bars on their inner edges are rabbeted to form the shoulders 11 and the glass grooves 12 for holding the pane of glass 13. The edge portions of the glass fit in the groove 12 and rest against the shoulders 11, and a line of putty or like material 14 while in a soft workable state is forced into the groove and against the side edge portion of the glass 80 and against the inner surface of the grooved portion of the sash bar. The exposed face 15 of the putty is beveled off from the glass to the frame edge and forms a strip of putty of triangular shape in cross section. While 85 in frames of ordinary construction the putty merely adheres to the sash it is the essential feature of this invention to provide in addition to the adherence a means for anchoring the putty to the sash frame. This 90 is accomplished by forming lines of indentations or recesses 16 and 16' in the inner face of the rabbeted portion of the sash. Some of these indentations in the sash extend in part beneath the edge portion of the 95 glass and others extend alongside of the side edge portions of the glass so that when the putty is forced into the groove portions in the form of projecting anchors 17 and 17' they will enter the indentations and 100 when the putty becomes hard, firmly anchor the putty to the sash. The anchors 17' will extend in part beneath the edge of the glass and be locked thereto.

In the modified form shown in Figs. 4 and 110

5 only two lines of indentations are formed into which the putty extends for holding the putty.

While indentations are shown for anchoring the putty it is to be understood that any roughening or cutting the surface which will permit the formation of anchors and the extension of putty beneath the edge of the glass will come within the spirit and 10 scope of the invention.

What we claim as our invention is:

1. A window sash, comprising a frame provided with a rabbeted portion forming a shoulder and with a recessed portion, said recess portion extending in part beneath the edge of the glass, a pane of glass having one of its side edge portions bearing against the shoulder, and a line of putty or like material engaging the opposite side edge of the pane of glass and the inner edge portion of the frame member, and entering the recessed portion of the frame member, and extending beneath the edge of the glass.

2. A window sash, comprising a frame member provided with a rabbeted portion forming a shoulder with a plurality of recesses extending in a line adjacent the shoulder, a pane of glass having one of its side edge portions bearing against the shoulder

and its edge portion extending over portions of the recesses, and a line of putty or like material engaging the opposite side edge portion of the pane of glass and the edge portion of the frame member and having anchoring portions which enter the line of recesses and extend beneath the edge of the glass.

3. A sash bar for a window sash, consisting of an elongated strip of material having a rabbeted portion forming a shoulder and also having a line of putty anchoring recesses extending adjacent to the shoulder and adapted to be partly covered by the edge of the glass mounted in the sash bar.

4. A sash bar for a window sash, consisting of an elongated strip of material having a rabbeted portion forming a shoulder and a groove and also having a plurality of lines of putty anchoring recesses, some of the recesses of the same line extending closer to the shoulder than others, said lines of recesses and the groove extending in lines parallel to the line of the shoulder.

In testimony whereof, we affix our signatures.

JOSEPH RAUWALD, SR.
FRANK RAUWALD.
